UNITED STATES PATENT OFFICE.

JOHN H. BAKER, OF ROYAL OAK, MICHIGAN.

MIXING DEVICE.

Application filed November 18, 1926. Serial No. 149,056.

This invention relates to a device for effecting the homogenization of combustible charges supplied to an internal combustion engine and has for its object the provision of 5 a simple and efficient device for the purpose, particularly adapted for ready application to the intake manifold of an engine and the construction of which is such as to insure a perfect mixture of ingoing air and fuel and 10 provide a device which may be cheaply manufactured. A further object is to provide a device having certain other new and useful features, all as hereinafter more fully described.

15 With the above and other ends in view, the invention consists in the matters hereinafter set forth and more particularly pointed out in the appended claim, reference being had to the accompanying drawing, in which—

20 Figure 1 is a perspective view of a device illustrative of the invention and showing the same as applied to the intake manifold of an internal combustion engine; and

25 Fig. 2 is a transverse vertical section through the device.

As shown in the drawing, 1 indicates the riser pipe, to the lower end of which the usual carbureter (not shown) is attached, and 2 indicates the engine intake manifold.

30 Interposed between the pipe 1 and manifold or formed as a part of the upper end of the pipe as shown, is a casing 3 forming a chamber, into the bottom of which the pipe opens. Formed integral with the manifold as shown 35 or as a separate part, is a cap, head or cover 4 for the casing 3, with the casing detachably secured thereto by providing a flange on the casing having holes to receive bolts 5 which engage screw-threaded openings in

40 the cap. The cap is preferably formed with an internal shoulder 6 against which is seated and secured in any convenient manner, a perforated plate or wire screen 7 which extends completely across the passage through 45 the manifold so that all gaseous mixture passing to the manifold will pass therethrough and be thoroughly broken up and mixed thereby.

To further break up the ingoing charges 50 from the carbureter, and provide a circuitous path for the same, a tube 8 arranged axially of the chamber 3, is seated in an annular seat 9 in the bottom of the chamber and surrounding the bore of the pipe 1, this tube 55 forming an upward continuation of the pipe 1 to near the upper end of the chamber 3.

A second tube 10 of greater diameter than the tube 8 surrounds said tube with a space or passage within the chamber between said second tube and the casing 3, said concentric tubes 8 and 10 being closed at their upper ends by a cap plate 11 having a peripheral annular notch or groove 12 to receive the upper end of the tube 8, and this cap or disk 11 is securely held in place and holds the tubes concentric, by means of bolts 13 or the like passing therethrough and clamping the tubes between the disk and the bottom wall of the chamber. The upper end of the inner tube 8 is provided with a series of openings 14 adjacent the disk 11 and the tube 10 is formed with a like series of openings 15 adjacent its lower end, and these openings 14 afford communication between the interior of the center tube or continuation of the inlet pipe 1 and the space or annular passage 16 between said inner and outer tubes, and the openings 15 afford communication at the lower end of the casing 3 between the passage 16 and the annular space 17 surrounding the tube 10 between it and the casing wall, said space 17 being open at its upper end around the disk 11 and between it and the wall of the cap 4.

Fuel vapor and air passing from the pipe 1 to the manifold 2 is thus caused to travel in a circuitous path, passing to the upper end of the center tube 8, through the openings 14, thence downward in the annular passage 16, through the openings 15 and then upward in the annular space 17 and out through the cap into the manifold. The space in the annular passage 16 is of slightly greater capacity than the capacity of the tube 8 and the capacity of the outer annular space or passage 17 is greater than that of the passage 16 so that the mixture of air and vapor expands from one passage into the next, thus aiding in the efficient mixing of the two, and the mixture as it passes the screen 7 is again broken up and intermingled, producing a final mixture entering the manifold having practically no globules of liquid of a size to be precipitated in passing through the manifold. A highly explosive mixture is thus delivered to the engine and any liquid fuel which may be precipitated in the passages 16 and 17 falls to the bottom thereof and will be swept out as the engine warms up and its speed increases. The holes 14 and 15 being small, serve as a multiplicity of jet openings from which the

mixture issues into the next succeeding chamber with high velocity and in a jet, thus further breaking up and intermingling the air and fuel.

- 5 With this particular construction, the device may be very cheaply manufactured as the tubes 8 and 10 are merely lengths of pipe cut to length and perforated to provide the holes 14 and 15, and these tubes are 10 simply set in place and secured in position by the securing of the disk 11 in place thereon by the bolts 13. A very efficient device for the purpose is thus provided, and one which may be quickly installed.
- 15 Obviously changes may be made in the construction and arrangement of parts within the scope of the appended claim without departing from the spirit of the invention, and I do not, therefore, wish to limit myself 20 to the particular form and arrangement shown.

Having thus fully described my invention, what I claim is:—

A mixing device of the character described comprising a pipe having an enlarged upper end forming a casing providing a chamber, a manifold formed with a

cap for said casing to close the upper open end thereof, said cap being formed with an interior annular seat, a perforate disk member seated upon and secured to said seat, an inner tube concentric with the opening of said pipe into said chamber and forming an upward extension of the pipe axially of the chamber, a second tube of greater diameter than the first tube and of lesser diameter than the casing arranged axially of the center tube, said tubes being seated upon the bottom of said casing, and a disk secured upon the upper ends of said tubes to close the same and clamp said tubes in concentric relation between said disk and bottom of said casing, said inner tube being formed with openings adjacent said disk affording communication between the interior thereof and the annular space between the tubes, and said outer tube being formed with openings near its lower end to afford communication between the lower end of the annular space between the tubes and the annular space between said outer tube and casing wall.

In testimony whereof I affix my signature.
JOHN H. BAKER.
